LOCK MECHANISM FOR EXTENSION
SLIDE TABLES

Benjamin A. Woina, Salem, and Archer W. Richards, Chagrin Falls, Ohio, assignors to American Fixture and Manufacturing Co., St. Louis, Mo., a corporation of Missouri

Application March 10, 1950, Serial No. 148,872

5 Claims. (Cl. 311—49)

1

This invention relates in general to extension tables and, more particularly, to certain new and useful improvements in lock mechanism therefor.

The primary object of this invention is to provide a table having two identical half-sections each comprising a top-forming member and two legs, and extensibly connected to each other by slide means comprising a pair of mutually slideable rail members.

It is a further object of the present invention to provide a table-extending slide having associated therewith a locking mechanism whereby the table sections may be locked in any desired position of extension.

It is an additional object of the present invention to provide a table-slide which incorporates a pair of mutually slideable rails which are adapted to exert a pressure upon ball bearings disposed between said rails to prevent said bearings from unauthorized free movement.

It is still a further object of the present invention to provide a ball bearing table-slide which is simple and economical in construction and can be readily fabricated from sheet metal or similar material.

With the above and other objects in view, our invention resides in the novel features of form, construction, arrangement, and combination of parts presently described and pointed out in the claims.

In the accompanying drawings (three sheets),

Figure 1 is a perspective view of an extension table constructed in accordance with and embodying the present invention;

Figure 2 is a bottom view of the table;

Figure 3 is a transverse sectional view taken along line 3—3 of Figure 2;

Figure 4 is a transverse sectional view taken along line 4—4 of Figure 3;

Figure 5 is a transverse sectional view taken along line 5—5 of Figure 4;

Figure 6 is a transverse sectional view taken along line 6—6 of Figure 2;

Figure 7 is a transverse sectional view taken along line 7—7 of Figure 2;

Figure 8 is an exploded view of the slide;

Figure 9 is an exploded view of the inner and outer rail prior to assembly;

Figure 10 is a fragmentary, longitudinal sectional view showing the slide in partially assembled position;

2

Figure 11 is a fragmentary, longitudinal sectional view showing the slide in fully assembled position; and

Figure 12 is a top plan view of the assembled slide.

Referring now in more detail and by reference characters to the drawings which illustrate a preferred embodiment of the present invention, A designates a table having a top 1 with an inset, 10 depending skirt 2 and comprising symmetrical sections 3, 4, which are normally in abutting relationship on their inner margins, as at 5. In its corner portions the table top 1 is supported by legs 6, each of which consists of a pair of brace members 7, 8, preferably of tubular stock, joined together, as by welding, between their lower and substantially center portions. In their upper portions the members 7, 8, curve divergently upwardly and inwardly and are each secured to the 15 downwardly depending flange 9 of an angle bracket 10 by means of a bolt 11 which extends through aligned apertures in the flange 9 and the walls of the members 7, 8, and has a washer 12 and nut 13 engaged on its projecting end (see Figure 7). The angle bracket 10 is secured to the under face of the table top 1 by its upper flange 14 which is provided with a plurality of apertures 15 for receiving screws 16 which are threaded into the table top 1. Thus, the legs 6 provide what might be called an eight point support and thereby makes the table A sturdy and rigid.

Provided on the under side of the table top 1 is a pair of spaced slides S in parallel relation, 35 and equidistant, to the longitudinal axis of the table top 1. Each of said slides S comprises an outwardly opening outer rail 17, fabricated of sheet metal and of general channel-shaped form, which is secured to the under face, and adjacent 40 the inner margin, of the section 4 of the table top 1 by a pair of spaced angle brackets 18 having downwardly directed flanges 19 which are welded, or otherwise secured, to the webs 20 of the rails 11, and horizontal flanges 21 which are secured 45 to the section 4 by screws 22. Referring to Figure 2, it will be noted that the rails 17 extend across the under face of the section 3 to a point immediately adjacent the end portion of the skirt 2, while the opposite ends of the rails 17 terminate approximately midway the length of 50 the section 4. Said rails 17 are provided with

horizontal flanges 23, 24, which have integrally formed therein longitudinally extending and inwardly opening grooves 25, 26, respectively. Provided for disposition within the rails 17 are inwardly opening channel-shaped inner rails 27, substantially narrower than the rails 17, and having flanges 28, 29, within which are formed outwardly opening grooves 30, 31, respectively, in registration with the grooves 25, 26, respectively, of the rails 17 to form raceways 32, 32', within each of which is disposed a pair of ball bearings 33, 33', and 34, 34', respectively. The rails 27 are secured to the under face, adjacent the inner margin, of the section 3 by means of a pair of spaced angle brackets 35 having depending flanges 36 secured, as by welding, to the webs 37 of the rail 27, and horizontal flanges 38, which are secured to the section 3 by screws 29. Referring to Figure 2, it will be noted that the rails 27 extend across the under face of the section 4 to a point adjacent the end portion of the skirt 2, with its other end terminating at a point substantially midway the length of the section 3.

The total length of the distance between the base portions of the grooves 30, 31, and the diameters of the ball bearings 33, 34, designated x and d in Figure 8, is slightly greater than the distance between the bases of the grooves 25, 26, designated y in Figure 8, so that the ball bearings 33, 33', 34, 34', will cause a flexure of the rails 17, 27, which, in turn, effects a pressure or so-called "pre-stress" upon said ball bearings 33, 33', 34, 34', to prevent unauthorized free rolling thereof within the raceways 32, 32'.

The flanges 23, 24, of the rails 17 are integrally provided, centrally, with a pair of vertically aligned downstruck and upstruck tabs 40, 40', and 41, 41', respectively. Similarly, the flanges 28, 29, of the inner rails 27 are integrally provided, centrally, with a pair of vertically aligned upstruck and downstruck tabs 42, 42', and 43, 43', respectively.

In assembling the slides S in the inner rail 27 is inserted partially into the rail 17, as shown in Figure 11. Thereupon, through one end of the rail 17, ball bearings 33, 34, are inserted into their respective raceways 32, 32', into adjacency with the tabs 42', 43', of the inner rail 27. Then detent tabs or end stops 44, 45, precut in the horizontal flanges 23, 24, respectively, proximate the adjacent end of the rails 17, are downstruck and upstruck, respectively, to prevent the ball bearings 33, 34, so inserted, from rolling out of the slides S. At the other end of the rail 17, ball bearings 33', 34', are inserted into their respective raceways 32, 32', to a point substantially adjacent the tabs 40, 41, of the flanges 23, 24, respectively. Thereupon, detent tabs or end stops 44', 45', precut in the horizontal flanges 23, 24, respectively, and adjacent the other end of the rail 17, are downstruck and upstruck, respectively, to prevent the balls 33', 34', from unauthorizedly rolling out of that end of the slides S.

Finally, adjacent each end of the rail 27, detent tabs 46, 46', and 47, 47', in the flanges 28, 29, respectively, are upstruck and downstruck, respectively. The rails 27 are then shoved inwardly within the rails 17 whereupon the ball bearings 33, 33', 34, 34', are engaged by the tabs 46, 42, 47, 43, respectively, of the rails 27 and are moved thereby into substantial abutment against the tabs 40', 44', 43', 41', respectively, of the rails 17, disposing said rails 17, 27, in maximum telescoped relationship, which, after the slides S have been affixed to the table top 1 by the brackets

18, 35, corresponds to the sections 3, 4, being in abutting relation, as shown in Figure 1.

Thus, when the user desires to extend the sections 3, 4, of the table top 1 to permit the insertion of a table leaf (not shown), in a conventional manner, the rails 17, 27, of the slides S, will extend in mutual longitudinal relation. Since the rails 17, 27, are each secured to but one of the sections 3, 4, the user, to effect such extension, need only pull outwardly upon either one of the sections 3, 4, and not upon both, as is requisite with slides in current use. Outward extended movement of the sections 3, 4, will be limited by the ball bearings 33, 34, being rolled into detaining contact by the tabs 42', 43', of the inner rail 27 against the end stops 44, 45, of the outer rail 17, respectively.

It is to be particularly pointed out, with reference to Figures 10 and 11, that the ball bearings 33, 33', 34, 34', will contact the various tab members, as described above, across the apertures of the respective tabs developed in the flanges 23, 24, 28, 29, by the forming of said tabs. Thus, the force effected upon the tabs by impact with the ball bearings 33, 33', 34, 34', will impart to the tabs a backward rolling tendency, which prevents the tabs from becoming flattened during long usage.

Provided at corresponding points in the web portions 20 of each rail 17, approximately centrally within the portions of said rails 17 and extending across the under face of the sections 3, is a rectangular aperture 48 through which projects, into the space between the flanges 28, 29, of the rail 27, one end of a locking plate 49 of a latch mechanism L. Adjacent its end margin, the said projecting end of the plate 49 is provided with an aperture 50 aligned with an aperture 51 of reduced diameter in an angle plate 52 having a horizontal flange 53, which is seated upon the upper face of the plate 49, and an upper flange 54, which is secured, as by welding, to the inner face of the web 20 of the rail 17 (see Figure 4). Projecting downwardly through the aligned apertures 50, 51, is a rivet 55, which is diametrically increased for relatively snug-fitting engagement within the aperture 50, and is further diametrically increased in its lower portion, which extends below the under face of the plate 49, and has disposed thereabout the loop of a spring member 56, one end of which extends within the rail 17 and abuts against the inner face of the web 20 thereof, while the other end is led outwardly through the aperture 48 adjacent the under face of the plate 49 and has its end extremity hooked or bent upwardly for projecting engagement within a suitable aperture in the plate 49. Thereby, the plate 49 is biased in an axial, parallel relation with the transverse center line of the top 1. The end margin of the projecting end of the locking plate 49 is cut away as at 57 and is rounded or arcuately formed in its remaining portion which is provided with a depending arcuate cam surface or flange 58 for normal abutment against the inner face of the web 37 of the rail 27. Adjacent its other end the locking plate 49 is provided with an aperture 59 through which extends the downwardly bent end 60 of a rod member 61, said end 60 being prevented from unauthorized upward movement through the aperture 59 by teat-like projections 62 adjacent its end extremity. The rods 61 extend in mutual converging relationship across the under face of the sections 3, 4, to a point substantially centrally of the under

face of the section 4 and in alignment with the longitudinal axis of the table top 1, whence said rods 61 are led, in adjacent relationship, parallel to the axial center line of the table top 1, to a point adjacent the end skirt 2 where said rods 61 are bent laterally outwardly to provide a handle member 63. The rods 61 are maintained in adjacency by means of a bracket member 64 having a flange 65 secured to the under face of the table top 1 by a screw 66, a downwardly directed arm 67 and a lower horizontal flange 68 upon which the rods 61 are supported. Suitably engaged upon the free end of the flange 68 of the bracket 64 is a hold-down member 69 having a flange 70 parallel to the flange 68 and disposed upon the upper faces of the rods 61, with its end retentively projecting through an aperture 71 in the arm 66 of the bracket 64 (see Figure 6).

To free the sections 3, 4, for extension, the user pulls the handle 63 outwardly causing the locking plates 49 to be swung about the rivets 55 thereby swinging the cam surfaces 58 out of engagement with the webs 37 of the rails 27. The rails 17, 27, are, thus, free for relative movement to extend said sections 3, 4. After the limit of extensible movement desired has been reached, the user releases the handle 63, thereby permitting the locking plates 49, through action of the springs 56, to be rocked into locked position, with the cam surfaces 58 returned to tight abutment against the webs 37, whereby further movement between the rails 17, 27, is prevented. It will be seen that by operation of the latch mechanism L the sections 3, 4, can be locked in any desired degree of extension.

It should be understood that changes and modifications in the form, construction, arrangement, and combination of the several parts of the extension table may be made and substituted for those herein shown and described without departing from the nature and principle of our invention.

Having thus described our invention, what we claim and desire to secure by Letters Patent is:

1. A locking mechanism for an extension slide table comprising a table top member having first and second sections adjustably connected by a slide comprising an outer rail having an aperture in one face thereof, an inner rail telescopically nested within the outer rail, and ball bearings disposed between said rails whereby said rails may be moved with relation to each other; said locking mechanism comprising a locking plate extending through said aperture and normally abutting on its projecting end against the inner rail, whereby the rails are fixedly maintained in relative position, and control means for optionally swinging the locking plate out of engagement with the inner rail to permit relative movement between said rails.

2. A locking mechanism for an extension slide table comprising a table top member having first and second sections adjustably connected by a slide comprising an outer rail having an aperture in one face thereof, an inner rail telescopically nested within the outer rail, and ball bearings disposed between said rails whereby said rails may be moved with relation to each other; said locking mechanism comprising a locking plate extending through said aperture and normally abutting on its projecting end against the inner rail, whereby the rails are fixedly maintained in relative position, a spring member associated with said locking plate for biasing it

into abutment with said inner rail, and control means for optionally swinging the locking plate out of engagement with the inner rail to permit relative movement between said rails.

5. A locking mechanism for an extension slide table comprising a table top member having first and second sections adjustably connected by a slide comprising an outer rail having an aperture in one face thereof, an inner rail telescopically nested within the outer rail, and ball bearings disposed between said rails whereby said rails may be moved with relation to each other; said locking mechanism comprising a locking plate extending through said aperture and normally abutting on its projecting end against the inner rail, whereby the rails are fixedly maintained in relative position, a spring member associated with said locking plate for biasing it into abutment with said inner rail, and elongated rod means secured to the other end of said plate for swinging said plate out of engagement with the inner rail to permit relative movement between said rails.

4. A self-locking extension slide comprising an outer channel having a U-shaped cross-sectional contour and integrally including a flat web portion and outwardly projecting marginal flanges, an inner channel of U-shaped cross-sectional contour and integrally including a web portion and outwardly projecting marginal flanges, said inner channel being dimensionally smaller than the outer channel for loose-fitting telescopic disposition within the outer channel, bearing means operatively disposed between the flanges of the outer and inner channels, respectively, for holding the inner channel in slidably shiftable spaced relation within the outer channel, a pivot-forming member rigidly mounted upon the web of the outer portion and located within the confines of the inner channel, a locking plate rockably mounted upon the pivot-forming member and being provided at its outer end with an arcuate eccentrically located face for locking engagement against the face of the web of the inner channel, spring means associated with the locking plate for normally holding said plate in locked engagement with the inner channel, and manually operable handle-forming means for optionally swinging said locking plate out of locked position, whereby to free said channels for relative sliding movement with respect to each other.

5. A self-locking extension slide comprising an outer channel having a U-shaped cross-sectional contour and integrally including a flat web portion and outwardly projecting marginal flanges, the web of the outer channel being provided with an aperture, an inner channel of U-shaped cross-sectional contour and integrally including a web portion and outwardly projecting marginal flanges, said inner channel being dimensionally smaller than the outer channel for loose-fitting telescopic disposition within the outer channel, bearing means operatively disposed between the flanges of the outer and inner channels, respectively, for holding the inner channel in slidably shiftable spaced relation within the outer channel, a pivot-forming member rigidly mounted upon the web of the outer channel adjacent to said aperture and located within the confines of the inner channel, a locking plate rockably mounted upon the pivot-forming member and being provided at its outer end with an arcuate eccentrically located face for locking engagement against the face of the web of the inner channel, said locking plate projecting at its other end outward-

ly through the aperture, spring means associated with the locking plate for normally holding said plate in locked engagement with the inner channel, and manually operable handle-forming means connected to the outwardly projecting ends of the locking plate for optionally swinging said locking plate out of locked position, whereby to free said channels for relative sliding movement with respect to each other.
